UNITED STATES PATENT OFFICE.

OSCAR M. ARNOLD, OF NEW YORK, N. Y.

DESIGN FOR A PARASOL.

SPECIFICATION forming part of Design No. 28,464, dated April 12, 1898.

Application filed January 8, 1898. Serial No. 666,109. Term of patent 3½ years.

To all whom it may concern:

Be it known that I, OSCAR M. ARNOLD, of New York city, in the county and State of New York, have invented and produced a new and 5 original Design for a Parasol, of which the following is a full, clear, and exact specification.

Reference is to be had to the accompanying drawing, forming a part of this specification, 5 in which the figure is a perspective view of a parasol, showing my design.

The invention relates to parasols to be used with tailor-made gowns, so that the ornamentation of the parasol corresponds to the trimming of the gown.

My design consists of an embroidered ornamentation A for each panel B, the ornamenta-

tion being a base-scroll A', from the middle of which rises a star-like figure A² with a finial A³.

The leading feature of my design consists 20 of the raised and continuous embroidery ornamentation A, confined within the contour of each panel B, the ornamentation being approximately triangular in its general aspect, with the base spreading along the base of the 25 panel and with the apex or finial pointing toward the apex of the panel.

I claim—

The design for a parasol as herein shown and described.

OSCAR M. ARNOLD.
